CLAIM

The ornamental design for a headphone cable skull, as shown and described.

DESCRIPTION

FIG. 1 is a front elevation view of a headphone cable skull showing my novel design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a perspective view of a headphone cable skull of the present invention.

The uneven broken line representations in FIGS. 1–7 are for illustrative purposes only and form no part of the claimed design.
